UNITED STATES PATENT OFFICE

THEODORE L. SMITH, OF DETROIT, MICHIGAN, ASSIGNOR TO CAILLE MOTOR COMPANY,
OF DETROIT, MICHIGAN, A CORPORATION OF MICHIGAN

PROPELLER

Application filed April 20, 1931. Serial No. 531,405.

This invention relates to propellers and control means therefor.

It is old in the prior art to provide marine propellers which have blades which may be adjusted to change their pitch, thereby enabling their driving motor which operates in one direction only to propel the boat forwardly and backwardly, or to idle without propelling the boat in either direction, without the use of a complicated gear shift mechanism. In my prior Patent 1,737,523 issued November 26, 1929, I disclose a marine motor of the outboard type provided with a propeller having adjustable blades. In my copending application, Serial No. 428,261, filed February 14, 1930, I disclose an improved motor and propeller unit of this kind, the improvement including improved control arrangements for adjusting the pitch of the propeller blades.

My present invention, which broadly is an improvement over the above mentioned patent and copending application, has for one of its objects the provision of an improved arrangement for locking the propeller blades in position independently of the shifting collar and fork, an arrangement which eliminates the stress and wear on this collar and fork occasioned by the thrust placed on it by the blades. With the present invention the blades are locked in position and at the same time the shifting collar and fork are permitted to float freely.

Another object is the provision of a new and improved control arrangement for adjusting the pitch of the propeller blades and particularly a new and improved control arrangement in which the control parts adjacent the propeller housing are encased in that housing and run in oil.

In the preferred embodiment of my invention, the propeller consists of a hollow hub having blade members pivoted on its opposite sides, the pivot member of each of these blades extending into the hollow interior of the hub and being provided with a pinion gear rigidly attached thereto. Fitted within the hub and around the shaft of the propeller is a rack which engages these gears and is shiftable longitudinally of the shaft

to adjust the pitch of the propeller blades. The rack is moved longitudinally of the propeller shaft by a fork located within the propeller housing and controlled by a lever and link arrangement connected to the tiller bar of the motor.

In the preferred embodiment of my invention, the blades are arranged so that when they are moved to one of their extreme positions the water pressure developed on their working surfaces as the propeller is rotated tends to rotate the blades about the pivots about which their pitch is adjusted in the direction in which they were last moved, thereby locking them in their extreme positions. The thrust developed in the blades is resisted by the rack which engages stop members in the propeller hub when the blade is in position to drive the boat forward, and which are resisted by a thrust bearing when the blades are in position to drive the boat backward. In either case the rack resists this thrust independently of the shifting fork.

When the blades of the propeller are set in neutral or are set in positions intermediate of their extreme position, they are held by the rack and tiller bar as before.

My invention will thus be understood by reference to the accompanying drawings in which a preferred embodiment of it is shown by way of example and in which:

Figure 1 is a fragmentary elevational view, partly in section, showing an outboard motor equipped with my improved propeller;

Figure 2 is a cross-sectional view taken along the line 2—2 of Figure 1 showing the propeller detail;

Figure 3 is an elevational view of the propeller;

Figure 4 is a cross-sectional view taken along the line 4—4 of Figure 3; and

Figure 5 is an elevational view of the propeller showing the blades in position to drive the boat in a reverse direction.

Referring now to the drawings in more detail, the motor indicated generally at 1 is hung upon the stern board 2 of the boat by means of a bracket 3 and is attached thereto by clamp 4. As shown the motor cylinder

is disposed horizontally and connected to a vertical drive shaft 5 located in the tubular casing 6. The details of the motor per se and its mounting upon the boat are not of the essence of the present invention and are more fully explained in my above mentioned patent, to which reference is here made for the details of this construction.

Located at the bottom of the tubular casing 6 is a propeller casing 7 in which the propeller shaft 8 is located, that propeller shaft being connected to the motor shaft 5 in any preferred manner such as by the bevel gears 9.

15 The propeller shaft 8 is supported in the propeller housing 7 by anti-friction bearings 10 and 11 which are arranged to rotatably support it and to resist the end thrust placed upon it by the propeller during its operation.

20 The shaft 8 extends through the rear wall member 12 of the propeller housing 7 and projects therebeyond, the hub 13 of the propeller being keyed to the projecting end of the shaft 8 by a key 19' and being formed to tightly fit into the opening 14 in the wall 12, as shown in Figure 2.

25 The propeller hub is hollow, and located in it is a shifting rack 15 which consists of a bifurcated cylinder having two arms located parallel to the shaft but spaced some distance away from it. These arms are provided with teeth 16 and 17 which engage pinions 18 and 19 respectively. The pinions are rigidly attached to the pivot shafts 20 and 21 of the propeller blades 22 and 23, which blades are thereby pivotally mounted upon the hub 13. Nuts 24 threaded onto the ends of the pivots 20 and 21 lock the pinions on the blades and the blades on the hub, these nuts being held against rotation on their threads by cotter pins 25.

30 The shifting rack 15 is threaded onto a sleeve 26 which surrounds the shaft 8 and is rotatable with respect thereto and also 45 slidable thereon. The attachment of the rack 15 to the sleeve may be made in any preferred manner such as by the screw thread as shown at 27. A shifting collar 28 engages the sleeve 26 through a thrust bearing 29, so that a movement of the collar 28 to the right in Figure 2 will move the sleeve longitudinally of the shaft 8. A second thrust bearing 30 bearing against the collar 28 and connected to the sleeve through a 50 washer 31 and a collar 32 provides for moving the sleeve to the left in Figure 2 when the shifting collar is moved in that direction.

55 As will be seen in Figure 1, the pintles 33 of the collar 28 are engaged by the forked lower end of a pivoted lever 34 located within the propeller housing 7 and pivoted within that housing at 35. The free end of the lever 34 is connected by a link 36 to the control rod 37 which in turn is connected to the tiller bar 38 which is pivoted at 39 to the

motor frame. A movement of the tiller bar in a vertical plane about its pivot 39 will move the control rod 37 and cause it to rock the lever 34 about its pivot 35 and thereby move the fork to shift the sleeve 26 and rack 15 longitudinally of the propeller shaft 8. The tiller bar is provided with a detent 40 engaging a rack 41 on the motor frame to lock it against movement in a vertical plane as will presently appear. The latch 40 is controlled in any preferred manner such as by a push button 42 located in the end of the tiller bar handle 43. It will be noted that the rack, sleeve, fork, lever and control rod arrangement herein described is the same as shown and fully described in my above mentioned copending application Serial No. 428,261, filed February 14, 1930.

45 Each propeller blade 22 and 23 consists of a disk portion 50 registering with and seated in a counterbore 51 in the hub, and the blade proper projects outwardly from the periphery of this disk member. As is clearly shown in Figure 3, the working face 52 of the propeller blade is offset with respect to the pivotal axis about which the blade is rotated by the rack 15. As a result of this arrangement, when the propeller shaft 8 and hub 13 are rotated in the direction indicated by the arrow (Figure 3), and the blade 23 has been rotated in a clockwise direction about its pivot to position it to drive the boat forwardly, the edge 53 of the propeller blade becomes the leading edge. As this leading edge 53 bites into the water in which the propeller is immersed, that water sets up a pressure against it and on the working face 52 of the propeller blade. Since this working face is out of the plane of the pivotal axis of the blade, this water pressure acts over a greater area of the working face 52 to the right of the axis of the pivot shaft on stud 20 than to the left of the axis of the shaft 20 and this develops a force in the propeller blade which tends to rotate the blade in a clockwise direction about its pivot. The greater area of the blade acted upon by the water pressure to the right of the dot and dash line a—a (Figure 3) than to the left of that line produces a turning tendency in the blade which turning tendency holds the blade in open or set position without locking the blade in such position through the shifting collar and without the stress upon the shifting collar and other parts where such locking is necessary.

50 The opposite blade 22 will of course be similarly positioned and the water pressure on its leading edge 54 will develop a pressure which because the blade is offset with respect to its pivotal connection will develop a torque tending to rotate the blade in a counter-clockwise direction, Figure 2. The turning tendency in this blade tends to hold it in open or set position as described in connection with the other blade. The torque of the blade

22 about the pitch adjusting pivot tends to move the rack to the left as viewed in Figure 2 to hold the stop pins 55 against the end wall 56 of the propeller hub 57.

5 I have provided stop pins 55 located in the free end of the rack 15 which are adapted to engage the end wall 56 of the propeller hub 57, so that the pressure developed by the water and transmitted through the blade and 10 its pinion the rack 15 is transmitted through the pins 55 to the propeller hub 13. This pressure is exerted in a direction longitudinally of the propeller shaft 8 and toward the rear end of the boat, that is, it is 15 in direct opposition to the main propeller thrust placed upon the shaft 8 by the propeller blades themselves. However, since the thrust developed by the tendency of the blades to rotate about their pivots is small 20 as compared with the driving thrust of the blades, the boat is moved forwardly. This arrangement of transmitting the thrust developed by the tendency of the blades to rotate about their pivots to the hub of the 25 propeller in a direction opposite to that placed upon the hub by the main propeller thrust, permits locking the blades in their forward position without increasing the frictional losses occasioned by this added end 30 thrust.

The working faces 52 of the propeller blades are slightly concave and the trailing faces 57 are convex, these blades being shaped so that the concave face 52 is the main working face when the propeller is positioned to 25 drive the boat forward.

When the propeller blades are rotated about their pivots to drive the boat in a backward direction, the blade 23 will be positioned as shown in Figure 5, and the sleeve 26 will be moved forwardly of the shaft 8 and made to bear against the thrust bearing 58 which surrounds that shaft. The leading edge 53 bites into the water as the propeller is rotated in the direction indicated by the arrow 40 and the force set up in the propeller blade falls along a line located to the left of the pivotal axis of the blade, Figure 5, and consequently the blade is under tension which tends to rotate it in a counter-clockwise direction. This tension transferred into torque by the offset relation of the blade to its pivotal axis is communicated through the pinion 19 and teeth 17 to the rack 15 and 45 thence to the sleeve 26, tending to urge that sleeve to the right against the bearing 58. The stationary race 59 of this bearing is abutted against a wall member 60 of the propeller housing 7, so that the end thrust of 50 the sleeve 26 is taken up by the bearing 58 independently of the shaft bearings.

60 Preferably the blades are designed so that they operate most efficiently when adjusted to drive the boat forward since it is in that 65 position that they will be most often used.

The thrust placed on the rack under these circumstances is acting toward the back of the boat, and there need be no bearing through which this thrust is transmitted to the shaft without introducing frictional losses. When the blades are set to drive the boat in a reverse direction the thrust is absorbed by a bearing, but because of the shape of the blades this thrust is small and no great losses are incurred. 75

If it is desired to operate the propeller in a position intermediate of its extreme position it must be locked and the pawl 40 is used for this purpose. When the blades are in neutral there is no thrust upon them in 80 either direction and the fork is not under thrust and may therefore hold the blades in place without loss.

The propeller casing 7 is divided into compartments by integrally formed interior walls, and the entire casing is made oil-tight so that the motor shaft 5 and the bearing 5', the bevel gears 9, the propeller shaft bearings 10 and 11, the fork bearing and the rack 85 within the propeller hub may all be immersed in oil or other suitable lubricant. The fork shifting lever is likewise encased in this casing and immersed in oil so that frictional losses in the propeller head are 90 maintained. 95

From the foregoing it will be apparent that I have devised a new and improved reversible propeller which is capable of locking itself in its extreme positions independently of this shifting fork, and that the arrangement thus disclosed accomplishes this purpose by simple and inexpensive parts which while once properly adjusted may be operated over a long period of time without further attention. As shown the invention is applied to an outboard motor, this disclosure being made by way of example only as the improved propeller assembly may be used in connection with any type of small 100 marine motor. 105

Having thus complied with the statutes and shown and described a preferred embodiment of my invention what I consider new and desire to have protected by Letters Patent is pointed out in the appended claims. 110

115 1. An adjustable propeller of the class described comprising a blade, and a pivot for said blade, said pivot being spaced laterally from one side of said blade in a plane generally normal to the side of the blade and intersecting the blade substantially centrally between the leading and trailing edges of said blade whereby the pressure upon the blade in operation acts upon a greater area of the blade in a direction tending to open the blade than in a direction tending to close the blade and at the same time the leverage in the blade against adjustment is substantially one-half the width of the blade. 120

125 2. An adjustable propeller of the class de- 130

- scribed comprising a pair of diametrically opposite blades, coaxial pivots for said blade, said pivots being offset laterally from the sides of the blades in planes generally normal to the sides of the blades and intersecting the blades substantially centrally between the leading and trailing edges of the blades whereby the pressure upon the blades in operation acts upon a greater area of the blades in directions tending to open the blades than in directions tending to close the blades and at the same time the leverage in the blades against adjustment is substantially one-half the width of the blades.
- 15 3. An outboard motor comprising a generally vertical tubular post, an under-water unit disposed at the lower end of said post and including a housing part, a partition dividing the interior of said housing part 20 into a pair of chambers, a drive shaft extend-

ing down through said post and into one of said chambers, a propeller shaft disposed generally normal the lower end of said drive shaft and geared to said drive shaft in one of said chambers, said propeller shaft extending through the partition and out externally of the housing through the other chamber, a bearing disposed in said partition for journaling said propeller shaft, a propeller on said shaft externally of the housing, a generally vertical propeller adjusting rod extending down along the post and entering the other chamber, and connecting means disposed in said other chamber and connecting the lower end of said rod and said propeller for adjusting the propeller by means of said rod.

In witness whereof, I hereunto subscribe my name this 11th day of April, 1931.

THEODORE L. SMITH.
